UNITED STATES PATENT OFFICE.

HENRY E. MOOMAW, OF CHATTANOOGA, TENNESSEE.

SHEET-METAL ROOFING-PLATE.

1,072,025.

Specification of Letters Patent. Patented Sept. 2, 1913.

Application filed January 15, 1913. Serial No. 742,157.

To all whom it may concern:

Be it known that I, HENRY E. MOOMAW, a citizen of the United States of America, and a resident of Chattanooga, county of 5 Hamilton, State of Tennessee, have invented certain new and useful Improvements in Sheet-Metal Roofing-Plates, of which the following is a full and clear specification, reference being had to the accompanying 10 drawings, in which—

Figure 1 is a perspective view of portions of a pair of roofing plates constructed and connected in accordance with my invention; Fig. 2 a vertical transverse sectional view 15 showing the manner of interlocking adjacent plates; and Figs. 3, 4 and 5 detail perspective views showing the application of my invention to three different designs of roofing plates.

This invention has relation to that type 20 of sheet metal roofing covered by my former Patent No. 884,285, dated April 7, 1908, in which is shown and covered a sheet metal roofing plate having an upstanding ridge 25 parallel with and a short distance from one edge and another similarly shaped and dimensioned ridge parallel with and a short distance from its other edge, the part of the plate outside of this latter ridge serving as 30 a nailing flange, a longitudinal pocket-like channel being formed inside of and adjacent to this latter ridge and opening toward the ridge and being less in height than the same, whereby the longitudinal edges of a series of 35 such plates may be overlapped and interlocked and the ridges of each pair of adjacent plates fit closely upon each other their entire length to form a reinforced upstanding ridge. Since the grant of this patent 40 this type of sheet metal roofing has been extensively manufactured and used and while it has proven of great practical and commercial value experience has shown that occasionally, by reason of the large sizes of the 45 roofing sheets, high winds will get under the sheets and balloon them sufficiently to unlock the overlapping edge of the upper sheet and furthermore severe contractions of the sheet will occasionally pull the lock flange 50 out of the lock fold and thus free the overlapping edge of the sheet.

My present improvement is designed to so 55 construct the interlocking joint as to prevent this disconnection of the plates, the construction being such that when the plates are once interlocked and nailed down it will be prac-

tically impossible to dislodge or disconnect them without first removing the nails in the nailing flanges. This improvement will be best understood if it be kept in mind that 60 this type of roofing plates is made in sizes very much larger than the well known metal shingles on the market, this type of roofing plate being designed to take the place of these comparatively small shingles.

In the drawing, the numeral 2 indicates the main body of the sheet, 5 the top wall of the lock channel or fold, 7 the channel, which faces toward the ridge formed by bending up the walls 8 and 9, this ridge and the channel 7 extending the full length of the sheet, and 10 the nailing flange. At the opposite edge of the sheet there is formed near its longitudinal edge a ridge having substantially the same shape as the ridge at the 75 other edge of the sheet consisting of the two walls 11 and 12; and beyond this ridge the edge of the sheet forms a locking flange 70 which is adapted to enter the channel 7. Each of the sheets is constructed in this 80 manner.

The walls 9 and 11 which form the walls 85 of the interlocking ridges at the side opposite the channel or lock fold are inclined, while the walls 8 and 12 of the interlocking ridges are vertical or at right angles to the main body of the sheet. The wall 11 is higher than the wall 9 so that when the walls 9 and 11 are fitted together, as shown 90 in Fig. 2, the wall 12 will stand at a distance from the wall 8, that is, nearer to the edge of the fold 5 than said wall 8. It will be observed also that the lip or flange 13 is so formed as to stand away from not only the body of the sheet but also the top wall 95 of the fold 5, the extreme edge of this flange 13 being bent upwardly so as to bear against the downwardly facing wall of the lock channel. With this construction it will be observed that should the overlapping sheet 100 be contracted or pulled laterally by wind getting under it, the wall 12 will be pulled squarely against the wall 8 and will thus afford a positive stop. It will also be observed that the space between the walls 8 and 12 allows for a reasonable degree of 105 expansion and contraction without bringing any strain on the sheets and it will be further observed that the space under the lock flange 13 and the said space between 110 the upright walls prevents water seeping past the joint by capillary attraction, there-

by rendering the joint water proof even during prolonged storms. The bending up of the extreme edge of the flange 13 converts said flange into a gutter to carry water away 5 from the joint and will tend to keep it from touching the under surface of the lock fold 5 and thus keep the joint as dry as possible. Should water get past the edge of the flange 13 it will be carried off by the gutter formed 10 by the wall 8 and the lock fold 5.

Having thus described my invention, what I claim as new and desire to secure by Letters Patent, is—

1. A sheet metal roofing plate having a 15 ridge parallel with and a short distance from one edge, one wall of this ridge being vertical and the other inclined, another similarly shaped ridge parallel with and a short distance from its other edge, the part of the 20 plate outside of this latter ridge serving as a nailing flange, and a longitudinal pocket like channel inside of and adjacent to this latter ridge and opening toward the same and being less in height than the same, the 25 inclined wall of said first named ridge being longer than the corresponding wall of the other ridge to extend above the apex of the same when adjacent plates are overlapped with their inclined walls in engagement 30 with each other, thereby assuring a relatively wide space between the vertical wall of said ridges.

2. A sheet metal roofing plate having a ridge parallel with and a short distance from one edge, said edge being bent to form 35 an edge channel, one wall of this ridge being vertical and the other inclined, a second similar shaped ridge parallel with and short distance from the other edge of the plate, said other edge adapted to serve as a nailing 40 flange, and a longitudinal pocket inside of and adjacent to this latter ridge and opening toward the same, the inclined wall of said first named ridge being longer than the corresponding inclined wall of the other 45 ridge to extend above the apex of the same when said inclined walls are in engagement with each other to form a relatively wide space between the vertical walls of said ridges, said vertical walls of both ridges being approximately the same length to position the bottom of said edge channel above the bottom of said pocket when said inclined walls are in engagement, to form a relatively wide space beneath said edge 50 channel and communicating with the space between the vertical walls.

In testimony whereof I hereunto affix my signature in the presence of two witnesses.

HENRY E. MOOMAW.
